UNITED STATES PATENT OFFICE.

FRANCIS LESLIE BUCK, OF BRISBANE, QUEENSLAND, AUSTRALIA.

SOUND-REPRODUCING MACHINE.

Application filed June 3, 1924. Serial No. 717,453.

To all whom it may concern:

Be it known that I, FRANCIS LESLIE BUCK, a subject of the King of the United Kingdom of Great Britain and Ireland, residing 5 at Kowa, Upper Kennedy Terrace, Paddington, Brisbane, Queensland, Australia, have invented new and useful Improvements in Sound-Reproducing Machines, of which the following is a specification.

10 This invention relates to improvements in sound reproducing machines, the object of which is to improve the tone.

The invention consists of a solid block of soft wood or other suitable material glued 15 into the neck of the tone chamber, the top of the block being flush with the sides of same, said block is provided with a circular passage, extending downwards for about two and a half inches, the wall of which is 20 left somewhat rough practically in the condition as when bored out by a bit.

The upper end of the block is attached to a superimposed flat piece of wood which may form a part of the bed of the instrument, or attached to the bed of the instrument, provided with a countersunk hole 25 having a composite stone surface for preventing the diffusion of sound which is directed by the circular passage through the tone chamber on to the sounding board which forms the bottom portion of the horn.

To fully describe the invention reference is now made to the accompanying drawings in which:—

Fig. 1, is a perspective view of the horn 35 and the tone chamber.

Fig. 2, perspective view to enlarged scale showing the block of wood or other suitable material glued into the neck of the tone chamber and attached to the superimposed 40 member.

Fig. 3, section of superimposed member showing countersunk hole.

Fig. 4, cross section through A—B of Fig. 2.

A is the horn, A' the tone chamber, B the solid block provided with circular passage B', C the superimposed member, C' the countersunk hole and C² composite stone coating.

The flanged end of the tone arm fits over the countersunk hole C' and is suitably attached to the superimposed member.

What I claim as my invention and desire to secure by Letters Patent is:—

A device of the class described, comprising a solid block of suitable material provided with a circular opening therethrough and adapted to fit into the neck of the tone chamber of a reproducing machine, and a 60 member superimposed on said block and having a countersunk opening in alignment with the opening of the block, said countersunk opening having its wall coated with a composite stone substance.

In testimony whereof I have signed my name to this specification.

FRANCIS LESLIE BUCK.
